(57) **CLAIM**

The ornamental design for a motor car, as shown and described.

DESCRIPTION

1. Motor car

1.1 is a top, front and left side perspective view of a motor car showing our new design;

1.2 is a front elevation view thereof;

1.3 is a rear elevation view thereof;

1.4 is a right side elevation view thereof;

1.5 is a left side elevation view thereof;

1.6 is a top plan view thereof.

1.1 is a top, front, and left side perspective view of a motor car embodying our new design; 1.2 is a front elevation view thereof; 1.3 is a rear elevation view thereof; 1.4 is a right side elevation view thereof; 1.5 is a left side elevation view thereof; and 1.6 is a top plan view thereof; this design is for a heavyweight article and therefore the bottom part of the article is omitted.
